UNITED STATES PATENT OFFICE.

GUSTAV N. MEVES, OF DAVENPORT, IOWA.

OPERATING MECHANISM FOR WASHING AND LIKE MACHINES.

1,086,547.

Specification of Letters Patent.

Patented Feb. 10, 1914.

Application filed December 18, 1911. Serial No. 666,459.

To all whom it may concern:

Be it known that I, GUSTAV N. MEVES, a citizen of the United States, and a resident of Davenport, in the county of Scott and State of Iowa, have invented certain new and useful Improvements in Operating Mechanism for Washing and like Machines; and I do hereby declare that the following is a full, clear, and exact description thereof, reference being had to the accompanying drawings, and to the characters of reference marked thereon, which form a part of this specification.

This invention relates to improvement in motor driven mechanisms for washing and like machines, and for wringers mounted on such machines, conveniently adaptable to such mechanisms as embody a main operating or stirrer head shaft to which is imparted rotary, reciprocatory motion.

Among the objects of the invention is to provide a simple, economical and efficient mechanism arranged to drive the main shaft or element, (the dasher shaft) and to drive the secondary shaft or element, such as a wringer roll shaft or shafts, in either direction, either independently of or simultaneously with the driving of the primary shaft.

Other objects of the invention are to improve the details of construction of such mechanisms and the invention consists in the matters hereinafter set forth and more particularly pointed out in the appended claims.

In the drawings:—Figure 1 is a rear view of the upper portion of a washing machine, and a wringer mounted thereon, equipped with my improved mechanism. Fig. 2 is a top plan view thereof, with parts omitted. Fig. 3 is a fragmentary view illustrating the clutch actuating mechanism for connecting and disconnecting the power to the main operating shaft. Fig. 4 is a detail, showing a latch for locking the swinging lid down. Fig. 5 is a detail of the fixed hinge plate and the hinge bearing and other lugs carried thereby.

As shown in the drawings, the tub 10 is provided with the usual swinging lid 11 that is hinged to the fixed or non-rising portion 12 of the tub top or cover. In the present construction the hinge connection between the fixed and swinging parts of the tub top embraces upright lugs 14, 14 which rise from a hinge plate 15 fixed to

the non-rising part of the tub top, other lugs 16, 16 which rise from a hinge plate 17 attached to the swinging portion of the tub top or lid, and a shaft 18 which has bearing 60 in and extends through alined apertures in said lugs. The said shaft 18 constitutes the pintle of the hinge, and is also rotatively mounted in the hinge lugs to constitute part of the driving connection that transmits power from the motor to the main operating shaft, as will hereinafter more fully appear. In this respect the construction is generally similar to the construction shown in my copending application for United States Letters Patent, filed on the 30th day of October, 1911, Serial No. 657,473. The said shaft 18, as in the latter described construction, is provided at one end with a crank 20 which is connected by a pitman 70 21 with a rocking sector 22 that meshes with a beveled pinion 23 which is fixed to the upper end of the main operating or dolly shaft 24, as in the construction shown in the aforesaid prior application. Loosely mounted on the other end of the shaft 18 is a worm gear 25 which meshes with a worm 26 that is fixed to a shaft 27 mounted in bearings 28, 28 formed on and rising from a rearwardly extending, depressed portion 29 of the plate 15. Fixed to the said shaft 27 near its outer end is a gear wheel 30 which meshes with a pinion 31 that is fixed to the shaft 32 of the motor 33. Said motor, which is herein shown as an 80 electric motor, is supported on the bracket 34 that is attached to the rear side of the tub and extends laterally outwardly. The said motor driven shaft 27 may also be provided with a belt pulley 35, made of any 90 diameter desired, and which may be driven from a motor located at any suitable point on the machine, or elsewhere, through the medium of a driving belt.

The shaft 18 is adapted to be locked to 100 and rotate with the worm gear by means of a clutch sleeve 37 non-rotatively mounted on said shaft and free to slide endwise thereof, said clutch sleeve being provided at its end with clutch jaws or teeth 40 adapted to engage like parts on the hub 41 of the worm gear 25, as shown in Fig. 2. The clutch sleeve is herein shown as connected to the shaft by means of a pin 38 which extends from the shaft through a slot 39 in the 110 clutch sleeve. The clutch is shifted on the shaft to engage it with and disengage it.

from the toothed hub of the worm gear by shifting devices made as follows: 45 designates an L-shaped shifter lever which is pivoted at the angle of its arms to a pin or stud 5 47 that is suitably mounted on the swinging portion of the lid. One arm of said shifter enters a deep annular groove 46 in the clutch sleeve and the other arm of the shifter is connected by a link 49 with one end of a 10 horizontal swinging hand actuated lever 50 that is pivoted between its ends to a stud 51 that rises from the swinging portion of the lid on the side thereof opposite to its hinge. The said clutch may be held in either its 15 clutching or non-clutching position, as by means of a leaf spring 53 that is attached to the lid 11 and is provided with a projecting portion 54 formed with double or oppositely facing shoulders to engage the correspondingly double faced oblique surfaces of 20 a V-shaped lug 55 on the lower side of the clutch actuating link 49. The resiliency of the spring permits the lug 55 to pass the projecting portion of the spring during the 25 shifting movement of the clutch, and the engagement of said spring with one or the other of the oblique sides of said lug serves to hold the clutch from accidental displacement and maintain it in its clutching or non- 30 clutching position. The relation of the shifter lever 45 to the clutch sleeve and the depth of the groove 46 is such that the free end of the shifter lever remains in said groove in all positions of the swinging lid, 35 on which the shifter is mounted.

If desired the hand actuated lever 51 may be provided with a latch or locking member 56 which is adapted to engage a notch 57 in a lug 58 that is attached to the side of the 40 tub and rises with its notched portion above said lid, so as to thereby lock the lid in its closed position. With this construction the lid is locked down when the clutch is in position to lock the worm gear to the shaft 18.

45 Mounted on the usual wringer board 60 at the rear side of the tub is a wringer 61, of common form. The shafts 63, 64 of the wringer rolls 62, 62, are rotatively mounted in bearings in the standards 65, 65 and are 50 provided at their ends with intermeshing pinions 66, 66. Mounted in bearings 68, 68 in said standards 65 and a bearing standard 69, rising from the hinge plate extensions 39 is a rotative shaft 70 which is provided near 55 the bearing standard 69 with a double faced gear, comprising the opposing beveled gear wheels 72, 72. Said beveled gear wheels are adapted for alternate meshing engagement with a beveled pinion 74 which may be integral with or attached in any suitable manner to the motor driven worm gear 25. As herein shown the said pinion 74 is made integral with said gear, and the pinion and gear are confined on the shaft 18 between a 60 collar 75 pinned to the shaft and the lugs or 65

arms 76 which rise from and are made integral with the hinge plate 15, as best shown in Figs. 2 and 5. The said shaft 70 has a limited endwise movement in its bearings whereby, upon shifting said shaft endwise, 70 one or the other of said beveled gears 72, 72 may be brought into mesh with the pinion 74, or both gears may be disengaged from said pinion to occupy a neutral position with respect thereto. The shifting of the shaft 75 70 is shown as effected by means of a shifter lever 78 that is pivoted at its lower end at 79 to a bracket 80 which is carried by the wringer board 60 or other fixed part of the machine. Said shifter lever 78 is connected 80 by a loose joint or connection at 81 to the adjacent end of the shaft 70, said joint being of a construction to accommodate the swinging movement of the shifter lever to the rectilinear movement of the shaft 70. The 85 lever 78 may be locked in different positions of adjustment to an apertured or notched sector bar 82, as by the pin 83, best shown in Fig. 1. Said bar 82 may be attached to the adjacent portion of the wringer frame. The 90 said shaft 70 is provided with a wide faced pinion 84 that meshes with a pinion 85 fixed to the extended end of the shaft 64 of the lower wringer roll, whereby the wringer rolls are driven from said shaft 70. The 95 wide face of said pinion 84 permits said pinion to be axially shifted with respect to the wringer shaft pinion 85, while maintaining proper meshing engagement between said pinions to effect the driving of the 100 wringer shafts from the shaft 70. By shifting said shaft 70 in one direction, one of the beveled gears 72 is brought into meshing engagement with the pinion 74 to rotate the wringer rolls in one direction. By shifting 105 the shaft 70 to the other limit of its movement, the other beveled gear 72 is brought into meshing engagement with the pinion 74 to rotate the wringer rolls in the opposite direction. The position of said shaft 70 intermediate the limits of its movement brings the beveled gear wheels 72 into neutral position with respect to the pinion 74 so that in such position of the parts no motion is transmitted to the wringer rolls. It will be thus 115 seen that the wringer rolls or secondary shafts may be rotated in either direction, either simultaneously with or independently of the operation of the main operating or 120 dolly shaft.

The driving and reversing gears are preferably housed by a gear casing 88, as shown in Fig. 1. This casing is omitted in Fig. 2 to thereby better show the arrangement of said gears.

It will be understood that the structural details of the mechanism shown may be somewhat varied within the spirit and scope of the invention and the invention is not therefore limited to such details except as 125 130

such limitations are imposed by the prior art.

I claim as my invention:—

1. Operating mechanism for washing and like machines embracing, in combination with a body, an operating shaft mounted therein capable of rotary, reciprocatory motion, a horizontal motor driven shaft at the top of said body provided with a worm, an intermediate horizontal shaft, means to operatively connect the intermediate shaft to said operating shaft, a worm gear on the intermediate shaft meshing with said worm, a motor for driving the motor driven shaft, and speed reducing gears interposed between the motor and the motor driven shaft.
2. Operating mechanism for washing and like machines comprising, in combination with a body, an operating shaft mounted therein, an intermediate shaft operatively connected thereto, a worm gear loosely mounted on the latter shaft, a motor operated shaft provided with a worm meshing with said worm gear, a clutch device for connecting the intermediate shaft with said worm gear, and a motor geared to the motor driven shaft.

3. Operating mechanism for washing and like machines comprising, in combination with a body, an operating shaft mounted therein, an intermediate shaft operatively connected thereto, a worm gear loosely mounted on the latter shaft, a motor operated shaft provided with a worm meshing

with said worm gear, a clutch device for connecting the intermediate shaft with said worm gear, a clutch shifter engaging said clutch device and pivoted to the body, a link pivoted to said shifter and extending across said body and means for locking the link and clutch from accidental displacement.

4. Operating mechanism for washing and like machines comprising, in combination with a body, an operating shaft mounted therein, an intermediate shaft operatively connected thereto, a worm gear loosely mounted on the latter shaft, a motor operated shaft provided with a worm meshing with said worm gear, a clutch device for connecting the intermediate shaft with said worm gear, a clutch shifter engaging said clutch device and pivoted to the body, a link pivoted to said shifter and extending across said body, said link being provided with a lug or projection having oppositely facing oblique surfaces, and a spring device mounted on the body and having correspondingly oblique surfaces to engage said lug or projection.

In testimony, that I claim the foregoing as my invention I affix my signature in the presence of two witnesses, this 11th day of December, A. D. 1911.

GUSTAV N. MEVES.
